CENTRIFUGALLY OPERATED BLADE FEATHERING DEVICE FOR PROPELLERS

Joseph H. Jacobs, Minneapolis, Minn.

Application November 13, 1943, Serial No. 510,116

3 Claims. (Cl. 170—75)

1

This invention relates to propellers for electric generators commonly known as wind electric devices.

Heretofore, devices have been utilized for varying the pitch of the blades of the propeller used to rotate the generator shaft.

The present invention relates to a propeller for a wind electric machine which is so constructed that the pitch is automatically varied in proportion to the speed of rotation and the centrifugal force to which the blades are subjected. This change of pitch can be termed an automatic feathering action.

One of the objects of the invention is to provide an automatic feathering set of blades which are normally held in their usual operating position but will move outwardly in their supporting shafts against some yielding means as the speed and centrifugal force due to higher wind velocity or a reduction in mechanical load increases. The yielding means, of course, returns the blades to their normal operating position as the speed and centrifugal force decrease.

Another object of the invention is to provide a propeller of the type described above wherein the yielding means connected to the blades is so constructed that should one such yielding means for its blade become broken or should its connection with the blade become broken all of the blades will automatically feather causing a lower operating speed and thus preventing unbalanced rotation of the propeller shaft upon the disabling of one of the blades.

Another object of the invention is to provide a propeller having blades which are capable of moving on their horizontal axes against the action of some yieldable means in addition to means for equalizing the amount of yieldable force exerted on all of the blades.

Still a further object of the invention is to provide linkage between the propeller hub unit and the propeller blades which will insure positive uniformity of pivotal movement of the blades as they are feathered under increasing centrifugal force.

These and other objects and advantages of the invention will more fully appear from the following description made in connection with the accompanying drawings, wherein like reference characters refer to the same parts throughout the views, and, in which:

Fig. 1 is a rear elevation of a propeller with portions broken away and other portions shown in dotted lines;

Fig. 2 is a section taken approximately on the line 2—2 of Fig. 1;

Fig. 3 is a perspective view of the equalizing plate.

Referring particularly to Fig. 2 there is shown a propeller shaft 4 having a tapered portion 5

2

upon which is mounted a hub unit indicated generally at 6. The hub unit 6 has a rearwardly extending sleeve-like portion 7 mounted thereon, and the left-hand or rear end of said sleeve-like portion 7 is provided with a flange 8. The forward end of the propeller shaft is reduced and threaded as at 9 to receive an outwardly extending post member 10, the latter acting as a nut to retain the hub unit 6 on the tapered portion 5 of the shaft 4. As shown in Fig. 1, the hub unit 6 is in the form of a spider, and said spider includes radiating web portions 6a.

Extending outwardly from the webs 6a in the hub 6 are rods 11 upon which are slidably mounted propeller blades 12, said blades being socketed and provided with bearing sleeves 12a which are in contact with the radial rods 11 extending from the hub webs 6a.

Connected to each of the blades 12 is a tension spring 13, the connection being in the form of an anchor bolt 14. The springs 13 extend radially inwardly from their anchor bolts 14 and are secured to a plate 15 which is hereinafter referred to as an equalizing plate. Said plate 15 lies against the outer end of the post 10 which, as stated above, extends outwardly from the end of the propeller shaft 14. It should be noted, however, that the equalizing plate 15 is not secured to the extended member or post 10 in any way.

Mounted upon the sleeve-like rearward extension 7 of the hub unit 6 is a collar 16 which is provided with short radial arms 17. Mounted in the end of each of the arms 17 is a spring socket generally indicated at 18. A side end portion of each arm 17 adjacent the spring socket 18 is provided with a tapered opening 19 to receive the ball-shaped end of a short arm 20 which is secured to a bracket 21 mounted on the end of each blade 12. The post 20 in each instance is secured to one side of the bottom portion of the blade, as best indicated in Fig. 1.

The tension springs 13 which are connected to the blades 12 and also to the equalizing plate 15 at the center of the unit and forwardly thereof are provided to maintain the blades at their normal working angle and to yieldably hold said blades in adjacent the hub unit 6. They do this in conjunction with the linkage comprising the collar 16, radial arms 17 and the short arms 20 which are connected to the blades. When the device is set up with the equalizing plate 15 lying against the outer end of the extension member 10 on the outer end of the propeller shaft 4 the pull of the various springs 13 on their respective blades is equalized by reason of the fact that the plate 15 will shift relative to the extended member 10 and thus balance the tensions of the spring.

When the apparatus attains sufficient speed and produces accompanying predetermined cen-

trifugal force, the blades will tend to move outwardly on the posts 11 which extend from the hub units 6 and a pull will be exerted upon the posts 20, and 17 and collar 16. The blades will thus be made to twist because of the linkage 17, 20 which will also move rearwardly with the collar 16, the latter twisting and sliding rearwardly on the rear sleeve-like extension 7 of the hub unit 6. Because of this linkage, all of the blades will twist or feather to the same degree. Continued outward movement of the blades 12 and further movement of the arms 17 and rearward movement of the collar 16 is prevented by reason of the flange 8 on the rear end of the sleeve-like portion 7 of the hub unit. This prevents the blades from assuming a dead center or over center position.

In addition to the equalizing effect of the disc 15 which connects with the inner ends of the tension spring 13 the structure shown and described has another very important advantage. Should one of the springs 13 or its connecting bolt 14 become broken or one of the blade assemblies the tension of the other two springs will pull the equalizing plate 15 from the forward end of the extended post 10 on the end of the propeller shaft 4, thus relieving tension on the two unbroken springs. As a result all three blades will automatically feather as they slide outwardly on their supporting rods 11, due to centrifugal force and the linkage 17, 20. This prevents any injury to the apparatus such as would happen if only one blade should become disconnected and feather leaving the other two in working condition and thus unbalancing the device to the extent that it might become seriously damaged.

While I have described the apparatus as being adapted for a wind electric machine or wind powered generator, it is, of course, to be understood that the propeller unit can be utilized for other purposes such as in ordinary windmill installations wherein the power is used to pump water.

It will, of course, be understood that various changes may be made in the form, details, arrangement and proportions of the various parts without departing from the scope of my invention.

What I claim is:

1. A centrifugally governed propeller for wind electric machines and the like, comprising, a rotary hub unit, centrifugally governed propeller blades extending radially outwardly from said hub unit and mounted thereon for pivotal movements about their central longitudinal axes, and for longitudinal movements radially of said unit, an annular member mounted for oscillation and also longitudinal sliding movement on said hub unit and carrying a series of circumferentially spaced, laterally extending ball sockets corresponding in number to said blades and directed generally towards said respective blades, each of said blades adjacent its inner end having an arm fixed thereto eccentrically of its longitudinal axis and adjacent its trailing edge and extended laterally toward one of said socket members and carrying a ball element connected with

its respective socket member and resilient means connected with said blades and exerting an inward longitudinal and radial pull thereon.

2. A centrifugally governed propeller for a wind-operated device comprising a rotary hub unit, a series of at least three centrifugally governed propeller blades extending radially outward in symmetrical arrangement from said unit and mounted thereon for pivotal movements about their central longitudinal axes and also for longitudinal movements radially of said unit, an annular member mounted for oscillation and also for longitudinal sliding movement on said hub unit and carrying a series of circumferentially spaced, universal connection elements corresponding in number to said blades and directed generally towards the inner end portions of said blades, each of said blades adjacent its inner end and trailing edge having an arm connected thereto at a point eccentric to its longitudinal axis, said arms extending angularly of said blades towards the respective universal connection elements of said annular member and each carrying a complementary universal connection element connected with its corresponding universal connection element on said annular member and resilient means connected with said blades for uniformly exerting inward, longitudinal pulls thereon.

3. A centrifugally governed propeller for wind-operated machines, comprising a rotary hub unit, precisely three centrifugally governed propeller blades extending radially outward from said hub unit and mounted thereon for pivotal movements about their longitudinal center lines and for longitudinal movements radially of said unit, an annular member mounted inwardly of said hub unit for oscillation and also longitudinal sliding movement on the inward portion of said unit and carrying at a radius somewhat greater than the maximum radius of said hub unit, a series of three circumferentially spaced universal connection elements directed generally towards the inner ends of said respective blades, each of said blades, adjacent its inner end, having an angulated arm connected eccentrically of the longitudinal axis of said blade and adjacent the trailing edge thereof and extending to the corresponding universal connection element of said annular member and terminating in a complementary universal connection element connected therewith and resilient means for uniformly exerting an inward pull upon said three blades.
